UNITED STATES PATENT OFFICE.

HERMANN BUSCHER, OF LANGERFELD, NEAR BARMEN, GERMANY.

LACE FABRIC.

1,024,247.

Specification of Letters Patent. Patented Apr. 23, 1912.

Application filed February 17, 1911. Serial No. 609,216.

To all whom it may concern:

Be it known that I, HERMANN BUSCHER, a citizen of the German Empire, residing at Langerfeld, near Barmen, in the Province 5 of Westphalia and Kingdom of Prussia, Germany, have invented certain new and useful Improvements in Lace Fabrics; and I do hereby declare the following to be a full, clear, and exact description of the invention, such as will enable others skilled 10 in the art to which it appertains to make and use the same.

This invention consists in a novel lace fabric constituting a new article of manufacture as hereinafter more fully described and claimed.

In the accompanying drawings: Figure 1 represents diagrammatically suitable mechanism for producing the said article; Fig. 2 20 represents a plan view of a piece of lace produced thereby and embodying said invention.

The texture 1 is formed in a well-known manner on a mandrel 3 supported on a 25 pillar and passing through the thread-collector 2, the fabric in the example illustrated being united at its edges to form a tubular structure by means of three auxiliary threads 4, 5 and 6. These auxiliary threads are worked in in the manner evident from Fig. 2, that is, the middle thread 5 twines alternately around the two others 4 and 6, the latter two threads being drawn 30 in the form of loops 4^a or 6^a through the marginal loops of the lace-fabric proper, so that when the middle thread 5 is removed the two other auxiliary threads 4, 6 can be 35 detached whole from the lace fabric. Above the thread-collector the mandrel 3 which is 40 round in cross-section up to that point becomes of the shape of a flattened tube and passes in a manner well-known in itself in the shape of an S around the drawing-off rollers 7, 8 provided above said thread-collector. Behind said rolls the mandrel has 45 again a round cross-section at its end part and at this part the rotary knives 9 revolving in the direction of the arrow are provided, which knives engage in grooves in 50 the mandrel and cut the loops of the middle auxiliary thread 5 near the loops 4^a, 6^a of the threads 4, 6 on the fabric moving over the mandrel. The various pieces of the thread 5 form the waste, while the threads 55 4, 6 which become free by said thread 5 being cut are wound on bobbins 10 or 11 so

that they can be used again. The texture thus opened is then delivered out of the machine passing in a flat condition over the roller 12. In order to clear the threads 4, 6, which are to be wound up, from the pieces of the thread 5 possibly still adhering to them, said threads 4, 6 are suitably passed through a thread-cleaner before they reach the bobbins 10, 11.

As is evident the fabric in the case of the process according to the present invention is passed through the drawing-off mechanism while still in the form of a tubular structure, so that it is impossible for it to become 70 distorted. In spite of this, however, the subsequent removal of the auxiliary threads by hand, which occupies extremely much time and is also expensive is avoided and further, some of the auxiliary threads are 75 regained.

What I claim as my invention and desire to secure by Letters Patent is:—

1. A textile fabric consisting of longitudinal parallel threads and pairs of additional threads passing in zigzag arrangement and opposite directions about said longitudinal threads and each other, auxiliary longitudinal threads 4 and 6, one of which is arranged within the border of each set of 85 threads aforesaid and in proximity to the inner longitudinal thread of that series and another auxiliary thread 5 extending in zigzag course from side to side of the space between the two longitudinal series first named 90 and engaging alternately looped portions of auxiliary threads 4 and 6, which portions extend inward between the inner longitudinal thread on each side and that part of one of the said additional threads passing 95 around the same substantially as shown.

2. A textile fabric consisting of longitudinal threads, additional threads arranged in pairs passing in reverse zigzag arrangement about said longitudinal threads at the borders of the fabric, auxiliary threads within the borders of the fabric and a zigzag thread which crosses from one border to the other alternately engaging said auxiliary threads and drawing them through the 100 proximate parts of the nearer members of the zigzag additional threads first above mentioned.

3. A textile fabric consisting of longitudinal threads, additional threads passing in 110 reverse zigzag arrangement about said longitudinal threads at the borders of the fab-

ric, auxiliary threads engaging said additional threads and a zigzag thread which crosses from one border to the other engaging alternately said auxiliary threads 5 and drawing them through the proximate parts of the zigzag additional threads first above mentioned.

4. A fabric provided with closing threads comprising four closing interlocking elements, the latter consisting of longitudinal threads, additional threads passing in a zigzag line about them, auxiliary threads in the two borders and a zigzag thread which passes from border to border alternately engaging said auxiliary threads and drawing them through the proximate parts of said zigzag auxiliary threads as set forth.

5. A textile fabric consisting of a plurality of sets of an odd number of longitu-

dinal threads, an auxiliary thread passing in longitudinal zigzag fashion around several of said longitudinal threads, including the central one thereof, another auxiliary thread passing in zigzag fashion around the 25 remainder of said longitudinal threads and the central longitudinal thread of each set and interlocking through the loop of the other auxiliary thread at the point of intersection with the central longitudinal thread 30 of each set, and threads connecting said sets of longitudinal threads.

In testimony whereof, I have signed my name to this specification in the presence of two subscribing witnesses.

HERMANN BUSCHER. [L. s.]
